UNITED STATES PATENT OFFICE.

JOSEPH H. BOURGON, OF DETROIT, MICHIGAN, ASSIGNOR TO THE STUDEBAKER CORPORATION, OF SOUTH BEND, INDIANA, A CORPORATION OF NEW JERSEY.

TOP CONSTRUCTION.

Application filed October 16, 1924. Serial No. 744,030.

This invention relates to automobile top constructions and particularly to tops for open types of automobiles provided with side enclosures movable vertically into the top 5 when placing them in inoperative position, and is particularly applicable to open type tops provided with roller curtains, such as is described in my previous patent application on top constructions filed July 9, 1924; Serial 10 Number 725,062, and certain features of which the present application constitutes improvements therein.

An object of the present invention is to provide a flexible curtain housing shield or 15 cover for a top of the class described.

Another object is to provide for a top of the class described, a flexible curtain housing shield provided with a stiffening member adjacent its lower edge.

20 Another object is to provide for a top of the class described, a curtain housing shield of flexible material, the lower edge of the shield being positioned adjacent the lower edge of the top frame and being reinforced 25 with a suitable stiffening member and the curtains being adapted to pass between said lower reinforced shield edge and the top frame lower edge which form a guide therefor at that point.

30 A further object is to provide in combination with a top for an open type automobile having curtains supported thereby and withdrawable vertically into operative position, a shield for concealing said curtains in said 35 top, said shield being formed of flexible material such as fabric and being secured adjacent its upper edge to said top, its lower edge being provided with a stiffening rod lying adjacent the lower edge of the top frame and 40 acting as a guide for said curtains when in operative or partly operative position.

The above being among the objects of the present invention, the same consists of certain features of construction and combinations of parts to be hereinafter described 45 with reference to the accompanying drawings, and then claimed, having the above and other objects in view.

In the accompanying drawings which illustrate a suitable embodiment of the present invention and in which like numerals refer to like parts throughout the several 50 different views,

Figure 1 is a perspective view of the upper portion of an automobile including a top

having curtains which are withdrawable vertically into the top for inoperative position, to which type of top this invention is applicable.

Figure 2 is a perspective view of the 60 frame of the top shown in Figure 1.

Figure 3 is a partly broken perspective sectional view through a portion of the top showing the manner of construction.

Figure 4 is a perspective sectional view 65 of part of the top showing the manner of mounting the curtains therein and the curtain housing shield.

Figure 5 is a sectional view through one side of the top showing the manner of 70 mounting the curtain housing shield and the manner in which it guides the curtains at the lower edge of the top.

Figure 6 is a perspective view of the upper end of the right front top support illustrating the manner of supporting the front 75 end of the curtain housing shield stiffening rod thereby.

Figure 7 is a perspective view of the right rear top support illustrating the manner of 80 supporting the rear end of the curtain housing shield stiffening rod thereby.

Figure 8 is a plan view of the curtain housing shield stiffening rod.

The top shown in the accompanying 85 drawings is substantially the same, except for the construction of the curtain housing shield and parts incidental thereto, as the top shown and described in my previous patent application, filed July 9, 1924, Serial No. 90 725,062, and the reference numerals, as far as possible, correspond to the reference numerals of that application in order to facilitate cross reference between the two. The

top frame is composed mainly of metal 95 stampings, as best shown in Figure 2, and consists of coved side members or quarters 30, coved rear member or quarter 31, front cross member 32 and a plurality of cross ribs 33. The side members 30 are preferably 100 formed of sheet metal and are constructed to serve as the top side quarters, that is to say, they curve upwardly and inwardly from their lower edge to form with the cross ribs 33 the frame for the flat upper portion of the top and they extend from the front cross member 32 rearwardly to the rear quarter 31, conforming in shape to that part of the finished top throughout. The rear quarter 31 curves upwardly and inwardly from the 105

110

bottom edge to the flat portion of the top in identically the same manner as the side quarters, and its ends are curved over to conform to the adjacent edge of the side quarters 30 and are suitably secured thereto by proper means such as welding. The front cross member 32 is preferably formed of wood to more easily attach the windshield 81 and rain shield 82 thereto. The lower edge of the side quarters 30 and rear quarter 31 is inwardly turned to form a horizontally extending flange 83 to which a tacking strip 62 is secured by screws or other suitable means. The upper horizontally extending inner edge of the side quarters 30 and rear quarter 31 is downwardly and then inwardly turned to form the horizontal flange 84 below the plane of the top for receiving and to which is secured the lower outwardly flanged edges of the inverted U sectioned ribs 33, the upper surface of which lies flush with the upper surface of the quarters. Alternate ribs 33 as shown are provided with wooden strips 34 lying against one side of the U and its corresponding flanged edge to serve as tacking strips for the top inner covering 44. The outer top covering 56 is brought over the ribs 33, quarters 30 and 31 and around the tacking strip 62 to which it is secured by tacking or otherwise along its upper inner surface adjacent the flange 83.

Suitable means, comprising front supports 47 and rear supports 48, are provided for supporting the top on the body 61, the front support 47 being positioned adjacent the front edge of the top and the rear support 48 being positioned substantially forward of the rear end of the top. A separately formed member 64, extending between the top and body and secured in place by suitable means such as screws, is provided at each rear corner to properly shape the top at this point. A groove 52 is provided in the rear edge of the front support 47 and a groove 54 is provided in the front edge of the rear support 48 for a purpose to be hereinafter described.

Welded, riveted or otherwise secured to the inner curved surface of the side quarters 30 are brackets 38 and 39 which are provided to support the roller curtains 41. Brackets for two of such curtains are provided on each side of the top, the rear curtains being arranged above the front curtains and the forward bracket of the rear curtain being arranged forward of the rear bracket for the front curtain so that the rear edge of the front curtain will overlap the front edge of the rear curtain and will effectually prevent the entrance of rain or dust therethrough. The front edge of the front curtain is received in the groove 52 of the front support 47, and the rear edge of the rear curtain is received in the groove 54 in the

rear support 48, which taken together with the overlapping meeting edges of the front and rear curtains forms a very effectual closure for the interior of the automobile against the elements. Suitable ears such as 85 at the upper edge of the groove 52 and 86 and 87 at each side of the groove 54 are provided for guiding the edges of the curtains into the grooves 52 and 54. It will be apparent that the side quarters 30 form a housing for the roller curtains 41, and it is in respect to a shield for concealing the curtains in this housing that this invention principally deals with.

Secured to the under side of each side quarter 30, adjacent the inner flanged edges 84 thereof by brackets such as 42 is a longitudinally extending strip 43 which serves as a tacking strip and support. The edges of the top inner covering 44 are tacked to the upper portion thereof and the material from which the shield 45, covered by the present invention, is made, is tacked to the lower portion thereof. The shield 45 may be composed of fabric extending over the length of the curtains and formed into a loop, the free edges of the fabric being placed in inverted position adjacent the lower edge of the strip 43 and being held in such position by a strip 88 through which tacks 89 or the like extend, passing through the fabric and into the tacking strip 43, thereby securely holding the shield 45 thereto. The fabric is then reversely bent over this strip, thereby connecting the same, and extends downwardly and outwardly therefrom, its lower looped edge being positioned adjacent the inner edge of the tacking strip 62. Extending throughout the length of this shield 45 and positioned in the lower looped edge thereof is a hollow rod 90 which acts as a stiffening member therefor and also for stretching the fabric to form a smooth surface. This stiffened lower edge acts as a guide for the curtains 41 at this point and keeps them, together with the inner edge of the tacking strip 62, in correct vertical position. To hold the lower looped edge in proper relationship to the inner edge of the tacking strip 62 and at the same time to properly stretch the fabric of the shield 45, the rod 90 must be securely held in place, and this is accomplished by slipping the forward end of the rod 90 over a pin 91 welded or otherwise suitably secured to the upper end of the front support 47 and extending rearwardly therefrom as shown in Figure 6, and providing the rear end of the rod 90 with a laterally extending arm 92 the free end of which is secured to the rear face of the rear support 48 by a screw 93 as shown in Figure 7. If the length of the shield 45 is such that the rod 90, supported at its ends only, might be subject to vibration, an intermediate arm such as 94 may be secured thereto

and a bracket such as 46 provided secured to the quarter 30 for receiving and to which the same may be secured. All that is necessary to gain access to the interior of the curtain housing if such is desired, is to remove the screw 93 and if the intermediate support 94 is employed, disengage the same from the bracket 46, and pull the rod 90 endwise off of the pin 91 which thereby allows the shield 45 to be swung back out of the way as illustrated in Figure 5 by dotted lines.

This shield construction has the advantage over the shield illustrated and described in my previous application referred to in that it is flexible and during "weaving" of the top does not tend to resist the strains set up thereby.

The construction is preferably such that the lower edges of the curtains are flush with the lower face of the tacking strip 62 when the curtains are in rolled or raised position, and in order to facilitate grasping the same to pull them down into operative position, it is desirable to form bends such as 95 in the rod 90 at a point adjacent the center of each curtain, which bends extend away from the tacking strip 62 and allow the entrance of a hand or fingers between the shield 45 and the tacking strip 62 for such purpose.

Formal changes may be made in the specific embodiment of the invention described without departing from the spirit and substance of the broad invention, the scope of which is commensurate with the appended claims.

What I claim is:—

1. In combination with a vehicle top having continuous coved sheet metal side quarters, the lower edge of each of which is inwardly turned to form a horizontal flange supporting a wooden member, roller curtains supported within said quarters, a flexible shield concealing said curtains when in rolled position, and a stiffening member for the lower edge of said shield positioned

adjacent to but out of contact with the inner edge of said wooden member to form a guiding slot for said curtains, said stiffening member and shield being movable out of adjacent relationship with said top to permit access to said curtains.

2. In combination with a vehicle top having roller curtains supported within its quarters, a fabric shield concealing said curtains when in rolled position, and a stiffening member secured to said shield along its lower edge, said member being bent inwardly adjacent the center of each curtain to facilitate the grasping of said curtains.

3. In combination with a vehicle top provided with roller curtains supported in the quarters thereof, a flexible curtain concealing shield secured to each side of said top above said curtains and provided with rod receiving means adjacent its lower edge, a rod within said means for stiffening said edge to provide a guide for said curtains, means for supporting said rod at its ends in adjacent relationship to the lower edge of said quarters, and means intermediate the ends of said rod for steadyng the same.

4. The combination with a vehicle top having side quarters, of a tacking strip secured adjacent the upper edge of said quarters, a tacking strip secured along the lower edge of said quarters, roller curtains mounted within said top, a flexible shield for concealing said curtains when in rolled position having one edge secured to said first-named tacking strip and having a loop formed at the opposite edge thereof, and a stiffening member for said flexible shield enclosed in said loop and secured to said top adjacent said second-named tacking strip to form a guide for said curtains when in unrolled or partly unrolled position.

Signed by me at Detroit, Michigan, U. S. A., this 10th day of October, 1924.

JOSEPH H. BOURGON.
